WILLIAM J. KELLY, OF READING, PENNSYLVANIA, ASSIGNOR OF ONE-THIRD TO
HARRY I. BERNHARD, OF BROOKLYN, NEW YORK.

METHOD OF MAKING STITCH-DOWN SHOES.

1,251,385.

Specification of Letters Patent. Patented Dec. 25, 1917.

Application filed October 17, 1912, Serial No. 726,206. Renewed September 21, 1917. Serial No. 192,631.

To all whom it may concern:

Be it known that I, WILLIAM J. KELLY, a citizen of the United States, residing at Reading, county of Berks, and State of Pennsylvania, have invented a certain new and useful Method of Making Stitch-Down Shoes, of which the following is a specification.

This invention is a departure in the manufacture of stitch down shoes, and a salient object of the invention is to produce a shoe of the character specified which can be readily re-soled. In the shoes of this character made heretofore, wherein the lining is lasted independently of the upper, it has been the practice to secure the outer sole directly to the upper, hence when the outer sole became worn or detached, the upper was left practically unsecured, and, accordingly, it was impossible for the ordinary cobbler or repairer of shoes to apply a new sole thereto.

In the present invention, the upper is secured to the insole, either by sewing or otherwise, whereupon the outer sole is attached by separate means to the insole and the upper. In a preferred form of construction a welt is employed, which rests upon the top of the outer edge of the upper, and together with the insole and outer sole, is secured to the upper.

In contradistinction to stitch down shoes heretofore constructed, the insole of the present shoe is channeled and slitted to provide upper and lower marginal flaps, the lower flap projecting beyond the upper flap and, in one embodiment of the invention the lining is secured, preferably by cement, within the slitted part of the insole, the edge of the lining extending inwardly and being attached by cement to the upper marginal flap, whereas the upper is attached to the lower marginal flap of said insole.

Other features of the invention, and the advantages thereof, will be apparent from the hereinafter detailed description.

In the accompanying drawings, I have illustrated a practical embodiment of the invention, but the constructions shown therein are to be understood as illustrative, only, and not as defining the limits of the invention.

Figure 1 is a side elevation illustrating the first stage in the operation of lasting an insole and an upper lining.

Fig. 2 is a cross section on the line 2—2 55 of Fig. 1.

Fig. 3 is a cross section similar to Fig. 2, but showing the operation of lasting the upper and attaching said upper to the insole.

Fig. 4 is a cross section similar to Figs. 60 2 and 3 showing the operation of attaching an outer sole and a welt to the edge portion of the insole and the outwardly folded edge of the upper.

Fig. 5 is an enlarged cross sectional view 65 through an edge portion of the shoe shown in Fig. 4.

Referring more particularly to the construction illustrated in Figs. 1 to 5, inclusive, A designates a last, B an insole, C an 70 upper lining, D an upper, E an outer sole, and F a welt, which parts are assembled and united in the following manner.

The last A may be of the usual or any preferred form, and to the upper face of this 75 last is applied insole B, the latter having a channel b producing a lip b' which is free at one edge. The insole is channeled along its edge by any usual or preferred means, thereby producing a lip b' which is free 80 with respect to the edge portion of the insole proper. After placing the insole upon the last, lining C is drawn tightly around the last in the usual way. The edge portion c of this lining is folded inwardly with 85 in the channel b of the insole. Said inwardly folded edge c is drawn tightly around the edge portion of the insole and below lip b' thereof. It is preferred to attach the inwardly folded edge c of the lining 90 to the edge portion of the insole. This attachment may be effected in any desired way or by any suitable means, but in one form of the invention the edge c of the lining is secured to the insole by an adhesive which 95 operates to retain the inwardly folded edge of the lining within the channel of the insole during the operations of lasting the upper and completing the shoe.

The next step in the operation is to last 100 the upper D. This lasting operation is carried out in the usual manner except that the edge portion of the upper is folded outwardly at d, and said upper is attached to the lip b' of the insole on a line well within 105 the outwardly folded edge d. The upper is drawn tightly around the last and the lasted lining in such a manner that a portion of

the upper will extend inwardly with respect to the lasted lining and with respect to a part of the channel in the insole, as shown more particularly in Fig. 5. By folding the 5 edge *d* of the upper outwardly, said upper is brought into lapping relation to the lip *b'* of the insole, the two edges of the upper and the insole being unattached at their free ends; but an important feature of the invention 10 consists in uniting the upper to the insole on a line within the unattached free edges thereof. This attachment of the upper to the insole may be effected in any suitable way, as for example by stitching the 15 upper to the insole, although it is preferred to unite the upper to the insole by an operation which practises the well known "stitch down" method. According to this operation the upper is lasted and its edge *d* folded outwardly as described, and while the upper is held taut a row of staples *G* is driven 20 through the upper and the lip of the insole, said staples passing from the outside of the upper through the material composing said 25 upper and the material of the insole lip *b'*. The ends of the staples may protrude beyond the material composing the insole lip *b'* so as to be clenched against the upper face of the insole, or these staples may be allowed 30 to extend beyond said face of the insole so as to become embedded in the material composing the outer sole *E* when the latter is assembled or attached. Although it is preferred to staple the upper to the insole according 35 to the stitch down method, it will be distinctly understood that the method is not restricted to the employment of staples for this purpose, for the reason that the upper may be attached to the lip of the insole by a row of stitches, or any equivalent fastenings, an essential feature of this part of the invention being that the means for attaching the upper to the insole shall be independent of the means for attaching the outer 40 sole and the welt to the shoe, and a further essential feature being that the attaching means for uniting the upper to the insole shall be positioned within the welt in order that said welt may conceal the attaching 45 means between the upper and the insole.

The next step in the operation consists in uniting the outer sole *E* and welt *F* to the insole and the outwardly folded edge *d* of the upper. This union is usually effected by 50 stitching the several parts together after they shall have been assembled, the line of stitches being indicated at *H*, although any other means for attaching the several parts may be employed. In this connection it is 55 desired to call attention to the fact that the seam *H* whereby the outer sole and the welt are attached to the insole and the upper is independent of the means *G* for attaching the upper to the insole, and, furthermore, 60 the welt is positioned exteriorly to the at-

tachment of the upper to the insole. By reference to Figs. 4 and 5 it will be noted that outer sole *E* is positioned over the last and the insole, whereas the welt *F* is positioned upon the outwardly folded edge *d* 70 of the upper, the outer sole and the welt being thus brought into proper relation to the insole and the upper, respectively, for the proper attachment of the parts. The welt *H* is below the folded edge *d* of the upper, 75 and the lip *b'* of the insole, and said edge *d* of the upper is intermediate the outer sole and the welt. This gives a desirable finish to the shoe and imparts to the outer sole the appearance of increased thickness. 80

As shown in Figs. 4 and 5, a suitable filling *I* may be placed between the inner sole and the outer sole, but the employment of this filling is not an essential feature and may be used or omitted at the option of the manufacturer. 85

After the lining shall have been lasted and attached to the insole, and prior to lasting the upper, a counter *J* is placed in position over the lasted lining and at the heel portion 90 of the shoe so that the counter will be incased between the lining and the upper when said upper is lasted and attached to the insole in the manner described.

It is obvious that the welt imparts to the 95 shoe the appearance of a Goodyear welt, but shoes embodying this invention can be produced more economically than ordinary shoes, and the shoe has the appearance of a thick outer sole. 100

A most important advantage secured by the invention is the facility of repairing or re-soling the shoe by an ordinary cobbler or shoe maker. When the outer sole is cut or detached from the shoe, the upper, the lining, 105 and the insole remain intact because the insole is attached to the lining and the upper. The new sole is placed in position and it is sewed through the edge of the insole and the upper to the welt; if desired the welt may be 110 allowed to remain in position when repairing the shoe or during such repair the welt and the outer sole may be sewed to the upper and the insole.

Having thus fully described the invention, 115 what I claim as new, and desire to secure by Letters Patent is:

1. The method of making stitch down shoes which consists in placing upon a last 120 an insole the edge portion of which is channeled and slitted to provide upper and lower marginal flaps, the lower flap projecting beyond the upper flap, lasting an upper lining and folding the lower marginal portion thereof inwardly within the slit between 125 said upper and lower flaps, lasting an upper and folding the lower marginal portion thereof outwardly upon said lower flap, stapling the outturned portion of the upper to the insole within the channel thereof in 130

such manner that the angle of the upper projects into the slit between said upper and lower flaps, placing an outersole in position for attachment to the insole, and then sewing the outer sole to the insole and the upper on a line exterior to the line of staples uniting the upper and insole.

2. The method of making stitch down shoes which consists in positioning upon 10 a last an insole the marginal portion of which is slitted to produce upper and lower marginal flaps, lasting an upper and an upper lining so that the marginal portion of said upper lining is positioned within 15 said slitted part of the insole, attaching an infolded angular portion of the upper substantially within the slitted part of the insole and to the lower flap thereof, and attaching an outer sole to the upper and the 20 lower marginal flap of the insole.

3. The method of making stitch down shoes which consists in placing upon a last an insole the marginal portion of which is slitted to produce upper and lower marginal flaps, separately lasting an upper and an upper lining so that the marginal portion of said upper lining is positioned within 25 the slitted portion of the insole, folding the edge portion of the upper in an outward 30 direction and into lapping relation to the lower marginal flap of the insole, attaching an angular inwardly lasted portion of the upper substantially within the slitted part 35 of the insole and to the lower marginal flap thereof, and attaching an outer sole to the lower marginal flap of the insole and to the outwardly folded edge portion of the upper.

4. The method of making stitch down shoes which consists in positioning upon a 40 last an insole the marginal portion of which is slitted for a distance less than the width of said insole to produce upper and lower marginal flaps, separately lasting an upper and an upper lining so as to position the 45 marginal portion of said upper lining within the slitted portion of the insole and to position an angular inwardly extending portion of the upper into contact with the lower marginal flap, separately attaching the marginal portions of the upper lining and the upper to the upper marginal flap and the lower marginal flap respectively, and attaching an outer sole to the insole and the upper.

5. The method of making stitch down 55 shoes which consists in positioning upon a last an insole the marginal portion only of which is slitted for a distance equal to a fractional part of the width of the insole so as to produce upper and lower marginal 60 flaps, separately lasting an upper and an upper lining so as to position the marginal portion of said upper lining within the slitted part of the insole, attaching the marginal portion of the upper lining to the 65 upper marginal flap of the insole, attaching

an angular inwardly lasted portion of the upper to the lower marginal flap of the insole, said attachment of the upper to the insole being separate from the attachment of the upper lining to said insole, and attaching an outer sole to the insole and the upper, said attachment of the outer sole being separate from, and on a line exterior to, the attachment of the upper to the insole.

6. The method of making stitch down 70 shoes which consists in positioning upon a last an insole the marginal portion of which is slitted for a distance equal to a fractional part of the width of said insole so as to produce upper and lower marginal flaps, separately lasting an upper and an upper lining so as to position the marginal portion of the upper lining within the slitted part of the insole, attaching the marginal portion of the upper lining within the channel of the 75 insole, stapling an angular inwardly lasted portion of said upper to the lower marginal flap of the insole, and attaching an outer sole to the insole and the upper, said attachment of the outer sole being on a line exterior to and separate from the attachment 80 of the upper to the insole.

7. The method of making stitch down 85 shoes which consists in placing upon a last an insole the edge portion of which is slitted for a distance equal to a fractional part of the width of said insole so as to produce upper and lower marginal flaps, lasting an 90 upper lining and folding the edge thereof inwardly and attaching said inwardly folded 95 edge within the slitted part of the insole, lasting an upper and folding the edge thereof outwardly with respect to the lower marginal flap of the insole, attaching an angular portion of the upper to the lower marginal 100 flap of the insole, placing an outer sole in position for attachment to the insole, and then attaching the outer sole and the outwardly turned edge of the upper to the lower 105 marginal flap of the insole.

8. The method of making stitch down 110 shoes which consists in placing upon a last an insole the edge portion of which is slitted for a distance equal to a fractional part of the width of said insole so as to produce 115 upper and lower marginal flaps, lasting an upper lining and folding the edge thereof within the slitted part of the insole, lasting an upper and folding the edge thereof outwardly with respect to the insole, attaching 120 the upper to the lower marginal flap of the insole, placing a welt in position to be attached to the outwardly folded edge of the upper, and then uniting an outer sole and the welt to the lower marginal flap of the 125 insole and the outwardly folded edge of the upper.

9. The method of making stitch down 130 shoes which consists in placing upon a last an insole the edge portion of which is slitted

- for a distance equal to a fractional part of the width of said insole so as to produce upper and lower marginal flaps, lasting an upper lining and folding the edge thereof 5 within the slitted part of the insole, lasting an upper and folding the edge thereof outwardly and into contact with the lower marginal flap of the insole, stapling the upper to the lower marginal flap of the insole, placing a welt upon the outwardly folded edge of the upper, and attaching an outer sole and the welt to the marginal portion of the upper and the lower marginal flap of the insole. 10 15 10. The method of making stitch down shoes which consists in placing upon a last an insole the margin of which is slitted for a distance equal to a fractional part of the width of said insole so as to produce upper and lower marginal flaps, lasting an upper lining and attaching the edge thereof within the slitted part of the insole, lasting an upper and folding the edge thereof outwardly with respect to the insole, stapling the upper to the lower marginal flap of the insole, and attaching an outer sole to the lower flap of the insole and to the outwardly extended portion of the upper. 20 25 20 25 25 30 35 11. The method of making stitch down shoes which consists in positioning upon a last an insole the margin of which is slitted for a distance equal to a fractional part of the width of said insole so as to produce upper and lower marginal flaps, lasting an upper lining and attaching the edge thereof within the slitted part of the insole, lasting an upper and folding the edge thereof outwardly with respect to the insole, stapling the upper to the lower marginal flap of the insole, said stapling being independent of the attachment of said lining within the slitted part of the insole, placing a welt upon the outwardly folded edge of the upper, said welt being positioned exteriorly to the line of attachment between the upper and lower marginal flap of the insole, and attaching an outer sole and the welt to the upper and the lower marginal flap of the insole. 30 35 12. The method of making stitch down shoes which consists in positioning upon a last an insole the margin of which is slitted for a distance equal to a fractional part of the width of said insole so as to produce upper and lower marginal flaps, lasting an upper lining and attaching the edge portion thereof to said upper marginal flap of the insole, lasting an upper and folding the marginal portion thereof outwardly with respect to the insole, attaching the upper to the lower marginal flap of the insole, and attaching an outer sole to the lower flap of the insole and to the outwardly extended portion of the upper. 40 45 50 55 60 65

In testimony whereof I have signed my name to this specification in the presence of two subscribing witnesses.

WILLIAM J. KELLY.
